FASTENER WITH LOCKABLE CAMPING HASP

Filed June 26, 1941

UNITED STATES PATENT OFFICE

2,300,509

FASTENER WITH LOCKABLE CAMMING HASP

Albert J. Komenak, Stamford, Conn., assignor to
 The Excelsior Hardware Company, Stamford,
 Conn., a corporation of Connecticut

Application June 26, 1941, Serial No. 399,827

11 Claims. (Cl. 70—76)

This invention relates to lockable hasp fasteners of the type in which the loop forming end of a U-shaped hasp swings to and from a position extending around and hugging the casing of its lock mechanism.

A lockable hasp fastener of this general nature is disclosed in my copending application, Serial No. 349,339, in relation to which the present improvements propose particularly to equip the looped nose of the hasp with a combined lockable and cam acting element adapted to partake in the double function, first, of automatically drawing tightly together the meeting edges of the lid and body of a trunk or like container and, second, locking the hasp in place when such lid and body edges are thus drawn tightly together.

One object of the invention is to provide hasp carried means for this purpose whose corresponding dimensions preferably shall not exceed the depth of the case of the lock mechanism at the front of the mounting or escutcheon plate in order that all parts of the lock may operate exclusively at the front of said plate and at the same time necessitate no increase in all-over depth of a fastener where shallow proportions are highly desirable.

A further object is to embody both the before mentioned locking means, and cam action or drawing-together means, in a single tongue of bent over formation which in the case of sheet metal construction may originate from the material that is removed from the sheet between the spaced arms of the U-shaped hasp.

A further object is so to form such tongue and so to cooperatively relate it to the shape of the lock case that this tongue shall become quite inconspicuous or practically concealed when the hasp is closed.

A further object is to provide the before mentioned tongue with a cam-like shape and disposition capable of performing a camming action cooperatively with the lock case and preferably throughout as large an angle of swinging movement of the hasp as is possible.

A still further object is to render the lock bolt virtually tamper-proof when it projects from its case in locking position by shielding the bolt by means of the hasp and also by additional guard means flanking the extreme end of the bolt.

These and other objects of the invention will appear from the following description of one mechanical form of the present improvements in which description reference is made to the accompanying drawing, wherein:

Fig. 1 is a perspective view of a complete lock-

able hasp fastener embodying the present improvements showing the hasp in closed position.

Fig. 2 is a different perspective view of the same fastener showing the hasp in open position.

Fig. 3 is a fragmentary view in front elevation showing the front wall of the lock case broken away to expose interior mechanism as viewed from section plane 3—3 in Fig. 4.

Fig. 4 is a view taken in central vertical section through the complete fastener on plane 4—4 in Fig. 3 looking in the direction of the arrows and showing the hasp operatively installed on slightly separated trunk lid and body parts.

Fig. 5 is a view similar to Fig. 4 showing the hasp thrust home into fully closed position and locked.

Fig. 6 is a front view of the lower or looped end of the hasp looking in the direction of arrow "6" in Fig. 5.

Fig. 7 is a plan view taken in section on the plane 7—7 in Fig. 6.

Fig. 8 is a view taken in section on the plane 8—8 in Fig. 6 looking in the direction of the arrows.

Referring to the drawing, the hinge abutment, illustrated herein in the form of housing 10, is provided with tongues (not shown) which penetrate its mounting plate 13 and are peened over against the back thereof to hold parts 10 and 13 together. By this means the hinge bar 14 of the loop-like hasp member 16 is pivotally anchored at the front or rounded closed end 17 of a bearing notch in the side walls of housing 10, being yieldingly pressed thereagainst by a leaf spring 19 which is secured by small rivets 21 to the mounting plate 13. The latter is adapted to be fastened, as by larger rivets 20, to the front wall of a container lid 12 which may be hinged in usual manner (not herein shown) to a container body whose front wall is shown at 11. Hinge bar 14 is provided with a flattened portion 24 separated from the arms 15 of the hasp by rounded journal forming portions 25. The flattened portion cooperates with spring 19 to urge the hasp into either of its positions shown in Figs. 2 or 5, while the rounded portions afford a bearing fit for the hinge bar 14 within the rounded ends 17 of the bearing notch. Mounting plate 13 is shaped to provide the usual dowel tongue 22 which projects downward beyond the housing 10 and beyond that edge of the container lid wall which abuts against the container body wall.

Rigid or integral with hinge bar 14 are two flat spaced hasp arms 15 which are joined at the loop-like nose portion 28 of the hasp, this

nose portion being lipped forward to facilitate finger grasp. In Fig. 1 the hinge abutment 10, arms 15 and nose portion 28 of the hasp are seen jointly to frame a lock case 32 hereinafter described. From the metal that is struck out of the blank when the hasp is made of sheet metal to provide the space between hasp arms 15 there may be formed the lockable tongue 25 provided with a keeper aperture 27 and whose top or cam surface is somewhat chamfered at 30 to assist in a camming operation hereinafter more fully explained. Where the hasp 16 comprises a casting or is constructed otherwise than of sheet metal, the camming and keeper tongue 26 may be formed by a projection in the nature of a lug integral with or fixed on the casting.

The locking mechanism of my improved fastener is contained within a lock case 32 which may be secured in well known manner to its mounting plate 31 by means of tongue-like projections 33 of its side walls which projections extend through slots in mounting plate 31 and are peened over against the rear surface thereof. Case 32 has its bottom end wall cut away at 36 to admit into such cutaway the camming and keeper tongue 26 of hasp 16. In entering such cutaway the chamfered top surface 30 as well as the entire projecting length of the keeper tongue will wipedly engage and cam progressively against the bottom front edge 35 of the lock case wall which borders on niche or cutaway 36 for a purpose hereinafter referred to.

Mounting plate 31 may be secured fixedly in usual manner, as by rivets 45, to the front wall of container body 11 in such position that the usual socket-like recess 59, which is formed between lock case 32 and a shallow backwardly dished marginal portion of mounting plate 31, may be entered by the before mentioned dowel tongue 22 of the hinge housing 10 when hinge abutment 10 adjoins the lock case 32 in edge-to-edge relationship as shown in Fig. 5. A flange-like guard lip or barrier 47 is struck forward from the material of mounting plate 31 leaving an aperture 29 in the latter which aperture accommodates if necessary the extremity of the hasp carried camming and keeper tongue when the hasp is closed.

The lock mechanism within case 32 may consist of conventional working parts. Herein is shown reciprocal sliding plate 38 provided with a projection 37 which serves as the bolt of the lock. Plate 38 has a vertically elongated aperture 42 through which extends the key barrel 41 of the lock, the latter being journaled by means of its rear end 43 of reduced diameter in a bearing hole in mounting plate 31. The front end 46 of the key barrel is journaled in the key hole 63 in the front wall of lock case 32 and the key barrel is retained axially by means of its thrust flange 51 at the rear of the keyhole.

Bolt plate 38 carries a forward projecting lug 62 which cooperates with a finger 63 projecting from tumbler 64, the latter being loosely pivoted on a stationary stud 58 so that this finger arrests movement of lug 62 except when tumbler 64 is wiped aside by turning of the key 49 preparatory to shooting out or retracting bolt 37. Stud 58 is fixed in an auxiliary frame plate 50 which is imprisoned between barrel flange 51 and tumbler 64 and whose edges fit the interior of lock case 32. In usual manner the concave portion 67 of the edge of tumbler 64 is adapted for coaction with the working edge of the key 49.

In the heel 68 of tumbler 64 is tightly fixed one

end 69 of a leaf spring 71 whose opposite or free end bears against the inside surface of the edge wall 72 of the lock case thus constantly urging pawl 64 counterclockwise or toward lug 62 of the bolt plate in Fig. 3. In usual manner the key 49 is inserted through keyhole 43 and through the configured slot 52 in barrel 41. Its working blade engages the edges of both tumbler 64 and bolt plate 38 which border on notch 53 acting first to thrust the tumbler aside against the resistance of spring 71 and thereafter to impel the bolt plate up or down with the further turning of the key for projecting or retracting the bolt.

In operation the lid 12 of the trunk, or other 15 piece of baggage, carrying hinge housing 10 is closed loosely toward the body 11 of the trunk in the usual way whereupon dowel tongue 22 enters recess 59 and prevents forward or backward displacement of hinge housing 10 relative 20 to lock case 32. Hence when the nose portion 28 of hasp 16 is forcibly swung manually from its position in Fig. 4 to its position in Fig. 5, the camming and keeper tongue 26 slidingly presses against the edge 35 of lock case 32 in a manner 25 to draw the lid 12 forcibly closer to and into tight contact with the container body 11. Keeper aperture 27 in tongue 26 is thus presented to the lock bolt 37 which may then be shot into engagement therewith by turning key 49 in barrel 41 counterclockwise in Fig. 3. This shifts the parts 30 of the lock mechanism from their positions in Fig. 4 to their positions in Figs. 3 and 5 and makes it impossible to swing hasp member 16 away from the position in which it straddles and hugs lock case 32. Thus tongue 22 is held in engagement with the edge 35 of the lock case in which position tongue 22 completely fills the cut-out 36 in a manner to form cooperatively with the front face of the lock case an approximately flush and 40 smooth overall front exterior of the fastener, devoid of cracks, crevices or projections which might be unsightly or tear garments or harm the hand of the operator.

To open the fastener, key 49 must be inserted 45 and turned clockwise to withdraw lock bolt 37 from keeper tongue 26 after which the hasp may be swung from its position in Fig. 5 to its position in Fig. 2. In this latter position it will be retained by leaf spring 71. To guard against un- 50 protected exposure of the extreme bottom end of lock bolt 37, guard flange 47 is seen to flank closely the entire width of this bottom end of the lock bolt in Fig. 5 thus preventing access to and unauthorized tampering with the lock. It will 55 be observed that the barrier or guard flange 47, together with nose portion 28 of the hasp and those portions of lock case 32 which border upon the niche or cut-out 36, form a fairly complete housing or enclosure for the projecting portion 60 of the lock bolt.

It will be appreciated that some of the advantages of this invention may be availed of if the cutaway 36 in the bottom of the lock case is dispensed with. In that case lock bolt 37 may be 65 shot out and retracted through a mere clearance affording slot or notch which could be provided in the bottom, and otherwise unbroken end wall of the lock case. The provision of cutaway 36 affords a socket-like engagement of tongue 26 with lock case 32 which tends to hold the separable parts of the fastener more ruggedly in designed alignment under rough usage to which articles of baggage and the like are commonly subjected.

Departure in details from the exact construc-

tions and relationships of parts herein disclosed may be resorted to within the scope of the present invention and the appended claims are intended to refer to and cover all substitutes and equivalents for constructions and relationships of such parts as would be suggested hereby and fairly come within the terms of the claims.

I claim:

1. In a lockable hasp fastening, the combination of, a lock case, a hinge abutment separable therefrom, a loop-like hasp member swingably connected to said abutment having spaced arms joined by a nose portion of said hasp member swingable with said arms to a position wherein said hinge abutment said arms and said nose portion jointly frame said lock case when the latter is near said abutment, a cam surface carried on said nose portion of the hasp member inclined with respect to the path in which said surface moves when said hasp member swings toward said position, a thrust edge on said lock case in a position to be wiped by the inclined length of said cam surface progressively for forcing the lock case toward said hinge abutment, a locking bolt projectable from said lock casing, and a strike engageable by said bolt carried by said hasp member intermediate the ends of said cam surface.

2. In a lockable hasp fastening for a container having body and lid sections, the combination of, a lock case on one of said sections, a hinge abutment mounted on the other of said sections adjoining said lock case in edge-to-edge relationship separable therefrom as the lid section opens, a loop-like hasp member swingably connected to said abutment having spaced arms joined by a nose portion of said hasp member swingable with said arms to a position wherein said hinge abutment said arms and said nose portion jointly frame said lock case when the latter is near said abutment, a cam surface carried on said nose portion of the hasp member inclined in relation to the path in which said surface moves when said hasp member swings, a thrust edge stationed on said lock case in a position to be wiped by a progressive length of said cam surface for forcing the lock case toward said hinge abutment, a locking bolt projectable from said lock casing, and a strike engageable by said bolt carried by said hasp member within the area defined by said cam surface.

3. In a lockable hasp fastening, the combination of, a lock case, a hinge abutment separable therefrom, a loop-like hasp member swingably connected to said abutment having spaced arms joined by a nose portion of said hasp member swingable with said arms to a position wherein said hinge abutment said arms and said nose portion jointly frame said lock case when the latter is near said abutment, a cam surface carried on said nose portion of the hasp member inclined in relation to the path in which said surface moves when said hasp member swings, a thrust edge stationed on said lock case in a position to be wiped by a progressively inclined length of said cam surface for forcing the lock case toward said hinge abutment, a locking bolt projectable from said lock casing, and an aperture within the area defined by said cam surface forming a strike engageable by said bolt.

4. In a lockable hasp fastening, the combination of, a lock case, a hinge abutment separable therefrom, a loop-like hasp member pivotally connected to said abutment having spaced arms joined by a nose portion of said hasp member

swingable with said arms in an arcuate path of travel to a position flanking said lock case when the latter is near said abutment, a rigid tongue carried on and projecting in part forward and in part rearward from said nose portion of the hasp member forming a cam surface whose working length is thereby prolonged from the rear to the front of said nose portion and is inclined with respect to the path in which said surface moves when said nose portion approaches its case flanking position, a thrust edge on said lock case disposed in said path of cam surface movement thereby to be wipingly engaged by said surface for forcing the lock case toward said hinge abutment, a locking bolt projectable from said lock casing, and a strike engageable by said bolt formed by said tongue.

5. In a lockable hasp fastening, the combination of, a lock case, a hinge abutment separable therefrom, a loop-like hasp member pivotally connected to said abutment having spaced arms joined by a nose portion of said hasp member swingable with said arms in an arcuate path of travel to a position flanking said lock case when the latter is near said abutment, a rigid tongue constituting a continuous leaf of sheet metal carried on and bent to project in part forward and in part rearward from said nose portion of the hasp member forming a cam surface whose working length is thereby prolonged from the rear to the front of said nose portion and is inclined with respect to the path in which said surface moves when said nose portion approaches its case flanking position, a thrust edge on said lock case disposed in said path of cam surface movement thereby to be wipingly engaged by said surface for forcing the lock case toward said hinge abutment, a locking bolt projectable from said lock casing, and a strike engageable by said bolt formed by said tongue.

6. In a lockable hasp fastening, the combination of, a lock case, a hinge abutment separable therefrom, a loop-like hasp member pivotally connected to said abutment having spaced arms joined by a nose portion of said hasp member swingable with said arms in an arcuate path of travel to a position flanking said lock case when the latter is near said abutment, a rigid perforated tongue constituting a continuous leaf of sheet metal beveled to decrease the thickness thereof at its free edge carried on and projecting in part forward and in part rearward from said nose portion of the hasp member forming a cam surface whose working length is augmented thereby and is inclined in relation to the path in which said surface moves when said nose portion approaches its case flanking position, a thrust edge on said lock case disposed in said path of cam surface movement thereby to be wipingly engaged by said surface for forcing the lock case toward said hinge abutment, a locking bolt projectable from said lock casing, and a strike engageable by said bolt formed by said tongue.

7. In a lockable hasp fastening, the combination of, a lock case having a niche interrupting the regular contour of its edge walls, a hinge abutment separable from said lock case, a loop-like hasp member pivotally connected to said abutment having spaced arms joined by a nose portion of said hasp member swingable with said arms in an arcuate path of travel to a position flanking said lock case on opposite sides of said niche, a rigid tongue carried on and projecting from said nose portion of the hasp member

shaped and positioned to be received into and substantially to fill said niche forming a cam surface inclined in relation to said path of travel, a thrust edge on said lock case stationed in the path of travel of said cam surface to be wiped by the progressive length of said surface for drawing said lock case toward said hinge abutment.

3. In a lockable hasp fastening, the combination of, a lock case having a niche interrupting the regular contour of its edge walls, a hinge abutment separable from said lock case, a loop-like hasp member pivotally connected to said abutment having spaced arms joined by a nose portion of said hasp member swingable with said arms in an arcuate path of travel to a position flanking said lock case on opposite sides of said niche, a rigid tongue carried on and projecting from said nose portion of the hasp member shaped and positioned to be received into and substantially to fill said niche forming a cam surface inclined in relation to said path of travel, a thrust edge on said lock case bordering on said niche and disposed in the path of travel of said cam surface to be wiped by the progressive length of said surface for drawing said lock case toward said hinge abutment.

9. In a lockable hasp fastening, the combination of, a lock case, a hinge abutment separable therefrom, a loop-like hasp member pivotally connected to said abutment having spaced arms joined by a nose portion of said hasp member swingable with said arms in an arcuate path of travel to a position flanking said lock case when the latter is near said abutment, a rigid tongue carried on and projecting from said nose portion of the hasp member forming a cam surface inclined in relation to the path in which said surface moves when said nose portion approaches said case flanking position, a thrust edge on said lock case disposed in said path of cam surface movement thereby to be wipingly engaged by said surface for forcing the lock case toward said hinge abutment, a locking bolt projectable from said lock casing, and a strike engageable by said bolt formed by said tongue, together with a barrier flanking the said tongue at the opposite side thereof from the said lock case when the latter is flanked by the said nose portion of the hasp member thereby to bar access to the end of the said locking bolt.

10. In a lockable hasp fastening, the combin-

ation of, a lock case having a niche interrupting the regular contour of its edge walls, a hinge abutment separable from said lock case, a loop-like hasp member pivotally connected to said abutment having spaced arms joined by a nose portion of said hasp member swingable with said arms in an arcuate path of travel to a position flanking said lock case on opposite sides of said niche, a rigid tongue carried on and projecting from said nose portion of the hasp member shaped and positioned to be received in and substantially to fill said niche forming a cam surface inclined in relation to said path of travel, a thrust edge on said lock case stationed in the path of travel of said cam surface to be wiped by the progressive length of said surface for drawing said lock case toward said hinge abutment, a niche bordered by the said thrust edge and adapted to receive and substantially be filled by the said tongue, and a barrier flanking the said tongue at the opposite side thereof from said lock case when the latter is flanked by the said nose portion of the hasp member thereby to bar access to the end of the said locking bolt.

11. In a lockable hasp fastening, the combination of, a lock case, a hinge abutment separable therefrom, a loop-like hasp member pivotally connected to said abutment having spaced arms joined by a nose portion of said hasp member swingable with said arms in an arcuate path of travel to a position flanking said lock case when the latter is near said abutment, a rigid tongue carried on and projecting from said nose portion of the hasp member forming a cam surface inclined in relation to the path in which said surface moves when said nose portion approaches said case flanking position, a thrust edge on said lock case disposed in said path of cam surface movement thereby to be wipingly engaged by said surface for forcing the lock case toward said hinge abutment, a locking bolt projectable from said lock casing, a strike engageable by said bolt formed by said tongue, a sheet metal mounting plate bordering the said lock case, and a flange-like lip struck up from the sheet metal of said plate in a position to flank the said tongue at the opposite side thereof from said lock case when the latter is flanked by the said nose portion of the hasp member thereby to leave an aperture in said plate receptive to the end of said tongue.

ALBERT J. KOMENAK.
